(57) **CLAIM**

The ornamental design for a personal blender, as shown and described.

DESCRIPTION

FIG. 1 is a front elevational view of a personal blender showing our new design;

FIG. 2 is a rear elevational view thereof;

FIG. 3 is a left side view thereof;

FIG. 4 is a right side view thereof;

FIG. 5 is a top plan view thereof;

FIG. 6 is a first perspective view thereof; and,

FIG. 7 is a second perspective view thereof.

The broken lines in the drawings illustrate portions of the personal blender which form no part of the claimed design.
